UNITED STATES PATENT OFFICE

135,771

DESIGN FOR A GARMENT RACK

Herbert B. Beidler, Chicago, Ill.

Application April 19, 1943, Serial No. 110,001

Term of patent 7 years

To all whom it may concern:

Be it known that I, Herbert B. Beidler, a citizen of the United States, residing at Chicago, in the county of Cook and State of Illinois, have invented a new, original, and ornamental Design for a Garment Rack, of which the following is a specification, reference being had to the accompanying drawing, forming a part thereof.

In the drawing:

ment rack illustrated in Figure 1, the opposite side of the garment rack being exactly the same as the view of Figure 2; and

Figure 3 is an end elevational view of one end of the garment rack shown in Figures 1 and 2, the opposite end of the garment rack being the same as the view shown in this figure.

I claim:

The ornamental design for a garment rack, as shown and described.

HERBERT B. BEIDLER.
